UNITED STATES PATENT OFFICE.

OSCAR A. OLSON, OF AMES, IOWA.

PENCIL.

1,262,972.

Specification of Letters Patent. Patented Apr. 16, 1918.

Application filed April 16, 1917. Serial No. 162,558.

To all whom it may concern:

Be it known that I, OSCAR A. OLSON, a citizen of the United States, and resident of Ames, in the county of Story and State of Iowa, have invented a certain new and useful Pencil, of which the following is a specification.

The object of my invention is to provide a pencil of comparatively simple, durable and inexpensive construction, having a casing made of opaque or transparent material, as may be desired, adapted to receive a strip of flexible material of such type as will carry a blank memorandum space, written, printed, or photographic matter, blue prints, etc., the parts being so arranged that by rotating a portion of the device the strip may be wound upon a central drum or the like, a portion of the strip being arranged to project from the casing, so that the strip may be drawn out any time.

A further object is to provide such a device from which the strips may be readily removed for replacement by others.

A further object is to provide such a device from which the pencil part is readily removable for permitting its use for writing on the strip mentioned.

With these and other objects in view my invention consists in the construction, arrangement and combination of the various parts of the device, whereby the objects contemplated are attained, as hereinafter more fully set forth, pointed out in my claim, and illustrated in the accompanying drawings, in which:

Figure 1 shows a side elevation of a pencil embodying my invention.

Fig. 2 shows a side elevation of a casing, illustrating the slot therein.

Fig. 3 shows a transverse, sectional view through the casing.

Fig. 4 shows a plan view of the combined reinforcement and clip for holding the pencil in a pocket.

Fig. 5 shows a side elevation of the pencil with the casing removed.

Fig. 6 shows a sectional view taken on the line 6—6 of Fig. 4, and

Fig. 7 shows a vertical, sectional view taken through the pencil shown in Fig. 1, the strip of flexible material being removed.

In the accompanying drawings, I have used the reference character *a* to illustrate a hollow cylinder preferably made of metal forming the casing of my improved pencil.

The casing *a* is open at both ends, and is provided with a longitudinal slot *f*. In one end of the casing *a* is mounted a suitable plug or the like *b*, which comprises a body of suitable material with a casing member preferably of metal surrounding the same. The casing member projects upwardly beyond the body and forms a receiver for a rubber tip *c*.

In the lower part of the body of the plug *b* is an opening to receive the upper end of a small cylinder *j*, which forms a drum for the flexible strip hereinafter referred to. In the cylinder *j* is a longitudinally arranged slot *p*.

At the end of the casing *a* opposite the one having the member *b* is a cylinder *g* having near its upper end an annular, outwardly extending rib *m*. The upper end *n* of the cylinder above the rib *m* is designed to be tightly received within the lower end of the casing *a*. Received in the upper end of the cylinder *g* is a plug 11 of suitable material having in its upper surface an opening to receive the lower end of the cylinder *j*, as shown in Fig. 7. The cylinder *g* is preferably provided on its inner surface just below the plug 11 with a lug 12.

Received in the lower end of the cylinder *g* is a pencil *h*, having a notch formed in its upper end to receive the lug 12; the pencil is designed to fit tightly within the cylinder *g*, so that when the pencil is rotated the cylinder *g* will rotate therewith.

When the parts are assembled, I provide a strip *d* having at its inner end a loop *v* through which is extended a wire *r*. The wire *r* and loop *v* are extended through the slot *p* and are received within the cylinder *j*.

The strip *d* is of some suitable material which may be written upon with a pencil or which may receive printed characters, or photographs or views.

The strip *d* may be wound upon the cylinder *j* by rotating the pencil *h*. The strip *d* extends outwardly through the slot *f* in the casing *a* and has at its outer end a hem or loop *u*. The strip *d* is detachable and interchangeable and may be removed or inserted at will.

Extended through the loop *u* is a rod *t* formed on one end of which is a spring clip *e* having at its end a curved clip *e*. The clip *e* is outside the hem or loop *u* and is designed to form a clip for holding the entire device in the pocket.

2
In the practical use of the device, the parts are assembled, and if it is desired to draw out the strip *d*, the user may grasp the clip *e* and pull the strip out, as shown in Figs. 1 and 6. The pencil *h* may be pulled out of the cylinder *g*, and used for writing on the strip *d*, if desired.

The strip *d* may be used for carrying telephone numbers, or other desired information or for receiving advertisements, views, general information, etc.

When the strip *d* has been used, the pencil *h* may be reinserted into the cylinder *g*, and rotated, thereby rotating the cylinder *g* and 15 the cylinder *j* for winding the strip *d* onto the cylinder *j*.

The member *b* is provided with an annular rib *g* for limiting the insertion of the lower portion *r* of the member *d* into the 20 casing *a*.

Some changes may be made in the construction and arrangement of the parts of my improved pencil without departing from the essential features and principles of my invention, and it is my intention to cover by 25 the claim of the patent to be issued upon my application any modified forms of structure or use of mechanical equivalents which

may be included within the scope of my claim.

I claim as my invention:

In a device of the class described, the combination of a casing having a longitudinally elongated slot in its wall, a hollow cylinder rotatably received in said casing having a slot in its wall, means for rotatably supporting said cylinder, said means comprising a plug in one end of said casing, a rotatable cylinder in the other end of said casing, means carried by said rotatable cylinder for supporting one end of said first cylinder, a strip of suitable material extended through both of said slots, means for securing one end of said strip within the first cylinder, a pencil having one end received in said second cylinder, said pencil and second cylinder having coacting means whereby when the pencil is rotated the second cylinder may be made to rotate for rotating said first cylinder and winding said strip thereon, said last described means being adapted to permit said pencil to be freely removed from the second cylinder by longitudinal movement.

Des Moines, Iowa, March 23, 1917.

OSCAR A. OLSON.
